[57] **CLAIM**

The ornamental design for a speaker component, substantially as shown and described.

DESCRIPTION

FIG. 1 is a front elevational view of a speaker component showing my new design;

FIG. 1a is a detailed exploded view of a section of the grid of the speaker component shown in FIG. 1;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof; and

FIG. 7 is an enlarged view of a portion of the grille shown in FIG. 1.
